UNITED STATES PATENT OFFICE

OMAR J. HOTALING, OF CARLSTADT, NEW JERSEY.

VENDING-MACHINE.

1,072,947.

Specification of Letters Patent. Patented Sept. 9, 1913.

Application filed May 1, 1912. Serial No. 694,340.

To all whom it may concern:

Be it known that I, OMAR J. HOTALING, a citizen of the United States, and a resident of Carlstadt, in the county of Bergen and State of New Jersey, have invented certain new and useful Improvements in Vending-Machines, of which the following is a full, clear, and exact description.

This invention relates to machines for vending and dispensing newspapers and other articles of similar nature, and has reference more particularly to a machine of this class with which suitable coin-operable mechanism for controlling the machine can be employed, and which can be used singly or in combinations of pluralities of units, each consisting of one of the machines.

The object of the invention is to provide a simple, efficient and economical machine for vending newspapers or other similar articles, which is compact in form, light in weight and requires comparatively little room, which is so constructed that a number of the machines can be arranged in combinations and positioned one upon the other, which can be manipulated easily and rapidly and with the exercise of little effort, from which the articles can be dispensed one at a time, with precision, and without danger of injury thereto, and which can have associated therewith any suitable coin-controlled mechanism for regulating its operation.

A further object of the invention is to provide a vending machine of the class described which is capable of automatic adjustment for articles of different dimensions, for example, for the purpose of dispensing newspapers of different thicknesses, which is so constructed that one operation must be completed before the next succeeding operation of dispensing an article can be commenced, from which but a single article can be dispensed at each operation, and which can be easily charged or loaded with the articles to be dispensed.

A still further object of the invention is to provide a vending machine of the class described, in which unauthorized or illegal removal of any of the contents is practically impossible, which cannot be operated when empty, as means are provided for preventing the introduction of a coin when the machine is in that condition, and which is provided with means to advertise the fact

that the machine is empty when the entire 55 contents has been dispensed therefrom.

The invention consists in the construction and combination of parts to be more fully described hereinafter and particularly set forth in the claims. 60

Reference is to be had to the accompanying drawings forming a part of this specification, in which similar characters of reference indicate corresponding parts in all the views, and in which— 65

Figure 1 is a vertical longitudinal section of a machine constituting an embodiment of my invention, showing the same partly filled with newspapers to be sold; Fig. 2 is a similar view, showing a machine empty; Fig. 3 70 is a similar view on the line 3—3 of Fig. 4, showing the machine open and in condition to receive a filling of newspapers; Fig. 4 is a vertical, transverse section of the machine; Fig. 5 is a plan view of the machine, showing the door removed; Fig. 6 is a fragmentary, vertical, longitudinal section, showing certain of the details of construction; Fig. 7 is a fragmentary, horizontal section showing certain of the details of construction of the 80 mechanism for preventing the introduction of a coin into the machine when the same is empty; Fig. 8 is a fragmentary, perspective view showing one of the feed regulators for controlling the dispensing of the 85 articles; Fig. 9 is a fragmentary, perspective view showing one of the parts for preventing the operation of the machine before the last preceding operation has been completed. Fig. 10 is a fragmentary, perspective view showing certain of the details of construction of the mechanism for preventing the introduction of a coin into the 90 machine when it is empty; Fig. 11 is a similar view showing part of the article-support 95 and of a member controlled thereby for operating the mechanism shown in Fig. 10; Fig. 12 is a fragmentary, perspective view showing in greater detail one of the elements illustrated in Fig. 10; Fig. 13 is a 100 plan view of a modified embodiment of the invention, showing the top removed, and having an article-support partly broken away to expose certain of the constructive details; Fig. 14 is a fragmentary, longitudinal, vertical section of a modified embodiment of the device, showing means for preventing the introduction of a coin into the 105

fact

machine when the same is empty, and means for advertising the fact that it is empty; and Fig. 15 is a fragmentary perspective view showing a feed regulator of modified form.

5 Before proceeding to a more detailed explanation of my invention it should be clearly understood that the present form of the machine embodies improvements upon 10 the vending machines disclosed in my co-pending applications, Serial No. 527,452, filed January 11, 1910 and Serial No. 617,369, filed March 28, 1911. The present embodiment of the invention, as well as those shown 15 in the applications above mentioned, is particularly useful in connection with newspapers or other periodicals, but it may also be advantageously employed for dispensing and vending other articles approximately 20 similar in form to folded newspapers, or of such shape as to adapt them for use with the machine. It can also be proportioned to handle articles of sizes other than those of newspapers or periodicals. The present 25 form of my invention is similar to that described in my co-pending application, Serial No. 617,369, in that it has a series of rolls, operable, as will appear hereinafter, to slide the topmost article from a pile with 30 in the machine and advance it to a slide or chute or dispensing opening through which it passes to the buyer, the series including an initial roll, operative to advance the article a certain distance to position it for engagement 35 between other rolls to complete the dispensing action. I have not described in detail any coin-controlled mechanism to be used with the machine, and it will be understood that any type of mechanism of this 40 class adapted for the purpose can be used. For example, that shown in my United States Patent No. 992,774, dated May 23, 1911. The present form of my machine includes the independently and automatically 45 adjustable feed regulators as well as the sectional article-support disclosed in my co-pending applications, but I do not wish to limit myself to the combination with these or others of the elements previously invented. 50 of the novel features herein disclosed. Certain of the details of construction shown for example herewith, form no part of the invention and can be varied in accordance with individual preference and special conditions, without deviating from the spirit 55 of the invention as defined in the appended claims.

Referring more particularly to the drawings, I provide a suitable casing for the 60 machine, fashioned from cast metal or any other material adapted for the purpose, and comprising a bottom 20, a top 21, a back 22, and sides 23 and 24. The casing is provided with a removable front consisting of 65 a closure 25 hinged at its lower edge to the

corresponding edge of the casing bottom, in any convenient manner. At the front edge, the top of the casing has a downwardly disposed flange or extension 26 against which the closure seats. Any suitable locking mechanism (not shown), can be employed for securing the front of the casing in its closed position. I prefer to provide the front with a panel 27 of glass or other transparent material behind which a sample 70 article can be positioned so that the nature of the contents of the machine can be readily ascertained.

At the right-hand side 23, of the casing, is located an operating member 28 consisting of a handle or lever having a suitable grip 29 by means of which it can be conveniently manipulated. The operating member is rigidly mounted upon a spindle 30 journaled in bearings of the double walls of the side 85 23. An arm 31 is located between the walls of the side 23 and is likewise rigidly secured upon the spindle 30, in parallelism with the operating member 28. It will be understood that in effect, there is one operating 90 member comprising the two elements 28 and 31. A helical spring 32 is wound about the spindle 30 and has one end rigidly secured thereto. The other end of the spring is attached in any convenient manner to an arm 95 33 loosely mounted upon the spindle and having a movable head 34 adapted to be engaged in any one of a series of openings 35 provided for the purpose, in the inner of the side walls 23. By suitably adjusting 100 the arm 33 the tension of the spring can be varied as may be convenient or desirable. The function of the spring is to maintain the operating member in a normal position, i. e., in the position shown in Fig. 1, and to 105 resist a forward movement of the operating member. Furthermore, the spring acts to return the operating member to its normal position after, during the operation of the machine, it has been pulled forward. Accordingly, the spring, as will appear more clearly hereinafter, serves to complete the 110 operation of dispensing an article from the machine.

Located between the walls of the side 23, 115 adjacent to the operating arm 31, is a pair of slightly curved bars 36, mounted in any convenient manner upon studs or projections 37 of the inner, side wall. Each bar has a plurality of ratchet teeth 38 and a 120 length or section 39 of smooth edge. At opposite ends, the bars have upwardly disposed fingers 40. Pivotedly mounted upon the operating arm 31 is a pair of double dogs 41 having angularly disposed sides 125 extended in opposite directions. Springs 42 tend to hold the dogs in normal positions. The dogs are so constructed that each is adapted to engage both of the ratchet bars, but not at the same time, so that when one 130

part of one dog is in engagement with one ratchet bar, the other part of the same dog is inoperative with respect to the other ratchet bar. The finger 40 of each ratchet bar serves when engaged by a dog at the end of the travel of the arm, to displace the dog from operative engagement with the corresponding ratchet bar. The purpose of this mechanism is to insure the completion of the movement of the operating member in one direction or the other before a return movement, *i. e.*, a movement in an opposite direction, is possible. It will be understood that, for example, during the forward movement of the operating member, the rearwardly disposed part of one of the dogs is engaged with the teeth of the outer ratchet bar, and consequently, this dog serves to prevent any return movement of the operating member until the latter has completed its forward movement, until the other part of the dog in question is brought into engagement with the finger 40 nearest the front of the machine. This engagement then serves to displace the dog from operative engagement with the outer ratchet bar, and will permit a return movement of the operating member. Similarly, the return movement of the operating member must be completed before a forward movement is again possible.

The operating arm 31 has, at the extremity, a segmental extension 43, provided at the forward end with an angularly disposed nose or projection 44. Adjacent to the segmental extension, the arm 31 has a slot or recess 45, and at the sides of the same is provided with a pair of ears 46. A threaded pin 47 is mounted in correspondingly-threaded openings of the ears, and carries an adjusting member 48 which can be moved to one side or the other by suitably turning the threaded pin. A chain 49, for a purpose which will appear hereinafter, has one end secured to the extension 43 of the operating arm, at the rear thereof, and has the other end secured to the adjusting member 48. The effective compass of the chain can be adjusted by moving the member 48 in one direction or the other.

Suitable coin-control mechanism (not shown in detail), is positioned between the walls of the side 23, at the front of the casing, and has associated therewith a coin chute 51 communicating at the outer end with a suitable coin inlet 52 formed at the front of the casing in a fixed wall thereof. A pivoted stop 53 is mounted upon the inner side wall 23 adjacent to the coin-control mechanism, and has at the end a V-shaped notch or recess 54 which receives the end of a pivoted tongue 55 constituting a part of the coin-control mechanism. In a normal position of the operating member the nose 44 thereof is in juxtaposition with the lower extremity of the tongue 55, and is likewise adjacent to the notch 54 of the stop. Normally, the tongue 55 is held against movement, by the coin-control mechanism, and is not free to swing in a forward direction until a coin has been introduced into the mechanism. As soon as that has been done, the tongue is released, and, consequently, an initial movement of the operating member permits the nose 44 of the same to displace the tongue, which in turn displaces the stop 53, so that the operating member is free to swing forward. As soon as this has occurred the coin can escape from the control mechanism, so that after the operating member returns to its initial position the parts 53 and 55 assume their normal, relative positions and the mechanism cannot be again operated until another coin has been inserted in the coin slot.

The inner side walls of the casing are provided with slots 56 constituting guides or tracks for carriers 57, which are arranged to slide vertically therein. A transverse bar 58 connects the carriers, and has mounted thereon a normally horizontal part 59 of a sectional article-support for the newspapers. Pivotedly connected at the forward edge of the part 59, by means of hinges 60, is a movable part 61 of the article-support, which tends normally to swing downward gravitationally, as is shown in Figs. 1 and 3. Strips 62 of rubber or other suitable material are fastened upon the support and afford a friction surface so that the pile of articles upon the support will tend to maintain its place. Journaled in suitable bearings 63 on the bottom of the casing, at the rear thereof, is a shaft 64 upon which is arranged a pair of strong, helical springs 65, each having one end secured to one of the bearings 63 and having the other end fastened to a collar 66 or 67 rigid with the shaft. The collar 67 constitutes a ratchet engaged by a dog 68, pivotally mounted at the bottom of the casing. The collar 66 is provided with a plurality of peripheral recesses 69 adapted to receive the end of a rod or other suitable tool, so that the shaft can be turned to vary the tension of the springs. The ends of the shaft 64 project between the walls of the casing sides and have rigidly secured thereto, between the walls, arms 70, pivotally connected by means of links 71 with the carriers of the article-support. The ends of the shaft, furthermore, have rigid arms 72 between the walls of the casing sides, these arms being provided with adjustable heads 73 to engage openings 73^a of the inner walls, so that the shaft can be held in different adjusted positions for the purpose of regulating the spring tension. A chain 74 has one extremity secured to one of the arms 70, and passes around a pulley 75 mounted upon the corresponding casing side, thence through an opening 76 in the casing side, 130

and has the other end secured to a lever 77. The latter has its rear extremity pivotally mounted at the back of the casing, and is arranged to swing across the bottom of the same. I provide a stop 78 at the bottom of the casing, for holding the lever in a position such that the arm 70 is depressed against the tension of the spring. It will be understood that by swinging the lever toward the casing side 24, and moving it into engagement with the stop 78, the article-support will be moved downward against the tension of the spring and held in this position so that the machine can be conveniently filled with articles to be dispensed. When the lever is released and allowed to swing into its normal position the spring on the shaft will raise the article-support and continue to carry it upwardly as the articles are dispensed one by one in a manner which will be described hereinafter.

25 Journaled in suitable bearings of the casing sides above the article-support, is a shaft 79 having mounted thereon a plurality of serrated rollers 80. One end of the shaft projects into the space between the walls of the casing side 23, and is provided with a loose sprocket 81 around which the chain 49 passes. A ratchet 82 is rigidly mounted
30 upon the end of the shaft and is engaged by the spring-pressed dog 83 carried by the sprocket. Accordingly, during a forward movement of the operating member the shaft 79 will be actuated, and turned in a forward direction. During the return movement of the operating member the shaft 79 receives no movement from the chain, and remains inoperative.

A stub shaft 84^a is journaled in a suitable bearing in the inner side 24, at the front of the casing. One end of the stub shaft projects into the space between the walls of the casing side 23 and has loosely mounted thereon a sprocket wheel 87 which is in operative engagement with the chain 49. A ratchet 88 is rigidly mounted upon the end of the said shaft and is engaged by a spring-pressed pawl 89 carried by the sprocket wheel. The opposite end of the stub shaft projects into the casing and is provided at the extremity with a square recess 84^b. A shaft 84, provided at the front of the casing in line with the stub shaft, is journaled with one end in the side 24, the opposite end being provided with a square projection 84^c engaging the recess in the end of the stub shaft 84^a. The shaft 84 is provided with a plurality of rollers 85 having their peripheries provided with surfaces 86 of rubber or other like resilient material. This engagement between the projecting portion of the shaft 84 with the recess of the stub shaft 84^a permits a rotary motion of the shaft 84 when the stub shaft is rotated. Above the shaft 84, and projecting into the space between the walls of the

casing side 23 is a stub shaft 90 having loosely mounted thereon a sprocket 91, in operative engagement with the chain 49. Rigidly secured upon the stub shaft is a ratchet wheel 92, the teeth of which are engaged by a spring-pressed pawl 93 carried by the sprocket wheel 91. The stub shaft and the shaft 84 are operatively connected by gearing 94. A shaft 95 is arranged above and substantially parallel to the shaft 84, and like the latter is provided with a plurality of rollers 96 having peripheries 97 of rubber or like material. The ends of the shaft 95 adjacent to the casing sides are journaled in a bearing brackets 98 having vertically extended slots 99 which allow the shaft 95 to move a limited distance up and down. At the right end, the shaft 95 is operatively joined to the stub shaft by means of a suitable connection 100, which constrains the shaft and the stub shaft to rotate together but permits the up and down play of the shaft 95. The arrangement of the shafts 84 and 95 and their connections is similar to that of the corresponding parts shown in my co-pending application No. 617,639.

31,033. The lower shaft 84 has its left-hand end journaled in a bearing 101 carried by a pivoted member 102. The latter has a hinged extension 103, the extremity of which seats in a recess 104 of the casing frame when the bearing is in an operative position. When the front of the casing is closed it serves to hold the bearing in place. When the front of the casing is opened, the bearing can be removed in order to permit the displacing of the lower shaft 84 and its rolls, for a purpose which will be pointed out hereinafter. Intermediate its ends, the shaft 84 is journaled in bearings 105 formed at the ends of the arms 106 pivotally associated at the upper extremities of supports 107 consisting of jointed rods, which are pivotally mounted in the casing at the front thereof.

As has already been stated, I employ in the present embodiment of my invention, independently and automatically operated feed regulators. Each of these consists of a frame 108 having an upwardly offset member 109 and a forwardly offset member 110 having a bar substantially parallel to the member 109. Each feed regulator has an extension 111 by means of which it is pivotally mounted at the end of an arm 112. The arms 112 are in turn pivotally mounted between the walls of the casing sides, so that the feed regulators project inwardly into the body of the casing through openings 113 in the inner side walls of the casing. Each regulator includes a fairly flexible finger 114 adapted to rest upon the top of the pile of articles when the regulator is in place, with the forwardly offset member 110 at the 115 120 125 130

front of the pile. At the end of the member 110 is a bracket 115 of tapered form, having a downwardly disposed length 116, which is positioned at the front of the pile of 5 articles. The bracket carries a cushion stop 117 of stepped or inclined form and corresponding in location and shape to the outwardly tapered or flared end 118 of the finger 114. The operation of the feed regulators in the present form of the invention 10 is similar to that of the corresponding devices shown in my co-pending application No. 617,369. It will be readily understood that owing to their pivotal mounting they 15 rest directly upon the pile of articles in the casing and adjust themselves to the articles. As the topmost article is dispensed from the support it must pass under the finger 114 and between the end 118 thereof 20 and the cushion stop 117, which prevents the escape of more than one article at a time.

In order to prevent unauthorized removal of any of the contents of the machine, I provide a movable closure 119 for the escape 25 opening or chute 120 of the casing front. This opening is so arranged that as a paper passes between the rolls 85 and 96 it will be advanced to the opening, and passes through the same to the purchaser. The closure 119 30 consists of a slightly rounded plate extending longitudinally of the outlet opening, and normally obstructing the same. The member 119 is supported by carriers 121 loosely mounted upon the shaft 95. Arms 122 are 35 likewise loosely mounted upon the shaft, adjacent to the carriers, and have bifurcated ends 128 engaging lugs 129 of the bearings 98. Journaled in the casing sides, slightly above and rearwardly with respect to the 40 shaft 95, is a third shaft 123 having pivotally mounted thereon arms 124, the forwardly projecting ends of which are operatively connected to the carriers 121 by means of links 125. The arrangement is such 45 that as one of the newspapers 126, or another article, passes between the rollers 85 and 96, which are normally in engagement, the upper rollers, and with them the shaft 95, are raised, the peculiar mounting of the shaft 95 permitting this 50 upward movement. The arms 122 have rounded ends in engagement with contact faces 127 of the arms 124, and swing upwardly with the movement of the shaft, 55 about the lugs 129, and thus raise the levers 124, which in turn swing the closure from its normal position. It will be understood 60 that this construction permits the movement of the shaft to be multiplied as it is transmitted to the closure. As soon as the article has passed from between the rolls and escaped through the outlet opening, the shaft 95 returns to its normal position and at the same time the closure returns to its obstructing position over the outlet opening.

The article-support, consisting of the parts 59 and 60 is similar in construction, function and operation to that shown in my co-pending application No. 617,369, with the exception, however, that I provide in the present form of the device, two arms 130 which are rigidly connected with the movable section 61, being carried by extensions 131 of the hinges connecting the support parts, the extensions projecting through 70 slots 132 of the inner side walls of the casing, the arms 130 being located between the side walls. The inner of the latter carry fixed stops 133 adapted to be engaged by the free ends of the arms. The stops are so arranged and the parts are so proportioned, that as the support moves upward, the pivoted section 61 thereof gradually moves into the plane of the normally horizontal part 59. When the support is in a depressed position the part 61 is angularly disposed relative to the horizontal part and inclined downwardly toward the front of the casing. The purpose of this construction is to allow for the greater height of the pile of newspapers at the front of the same, owing to the greater thickness of the folded edges. 80

In order to prevent the introduction of coins into the machine when the same is empty, I provide automatic mechanism for 90 closing the coin chute when the last article has been dispensed. This mechanism includes a slot-closure operating rod 134 which is pivotally secured to the inner side wall 23, adjacent to the upper end of the slot 132, so 95 that when the support moves into its highest position, after the last article has been moved from the support, the extension 131 of the hinge at that side of the wall, will engage the member 134 and raise the same. A 100 bracket 135 is pivotally mounted upon a projection 136 of the inner side wall 23, and has a laterally disposed extension 137, under which the free end of the member 134 engages. A bar 138 has a laterally disposed 105 end 139 provided with an opening 140 which receives a downwardly directed stud 141 of the bracket 135. The bar is arranged adjacent to the inner side wall 23, and has at the end, a slot 142 through which projects a 110 screw extension 143 at the end of the projection 136, so that the bar 138 is capable of movement in the direction of its length. Movable mounted in ears 145 of the coin 115 chute 51 is a rod 146 having a laterally disposed end 147 mounted in an opening provided for the purpose, at the end of the bar 138. The rod 146 has associated therewith a laterally disposed closure 148 which is 120 adapted to be moved across the opening of the coin chute, to prevent the introduction of coins. In a normal position of the parts, the closure 148 is inoperatively disposed and the coins can freely pass through the coin 125 chute. When the last article has been dis- 130

pensed from the machine, the member 134 is engaged by the hinge 131 and is swung upwardly, rocking the bracket 135, which in turn moves the bar 138 in the direction of its length. This swings the rod 146 about a vertical axis, and brings the slot closure 148 into a position such that it obstructs the entrance to the chute.

When the machine is empty, and it is desired to refill it, the hinged front 25 is unlocked and swung outwardly into the position indicated in Fig. 3. The bearing 101 is then displaced, so that the shaft 84 can be swung outwardly and drawn from the casing, as is indicated in dotted outline in Fig. 3. The lever 77 is then swung into position at the back of the stop 78, and the article-support is thereby moved into its lowermost position. A pile of newspapers or other articles can then be easily slid into the casing and properly positioned upon the support. The lever is released and the support rises under the influence of its springs until the topmost article of the pile is brought into operative engagement with the serrated rollers of the shaft 79. The shaft 84 is thereupon returned to its operative position, and the casing is closed, whereupon the machine is ready for use. In order to prevent the feed regulators from interfering with the charging of the machine I provide means for automatically holding them in raised and inoperative positions when the casing is open. Each of the feed regulators, for this purpose, has an arm 149 extending forwardly from the member 109, and operatively connected by means of links 150, with arms 151 rigidly secured to and projecting rearwardly from the shaft 123. The latter has a crank 152 to which is pivotally connected a rod 153 which extends in a forward direction and has associated therewith a spring 154. The rod 153 projects through an opening 155 in the front flange 26 of the casing, and the spring, which is secured at the inner side of the flange, and is likewise secured to the rod 153, tends to pull the same forwardly and project it through the opening. This movement of the rod is transmitted to the shaft 123 and tends to rock the same in a forward direction, thereby raising the arms 151 and likewise raising the feed regulators, as is shown in Fig. 3. When the front of the casing is in place it engages at the projecting end of the rod 153, and forces the same inwardly and holds it in a normal position such that the shaft 123 and the feed regulators are in normal positions, and the latter rest upon the topmost article of the pile carried by the support.

After a coin has been inserted in the coin slot and the operating mechanism has thereby been released, a forward movement of the operating member rotates the shaft 79, the serrated rollers of which advance the

topmost article of the pile through the feed regulators, and into position between the rollers of the shafts 84 and 95. Upon the return movement of the operating member these shafts are rotated, and continue the forward movement of the article, which is thereby ejected through the outlet opening of the casing, the closure of the same having first been inoperatively disposed, as has already been described. As the articles are dispensed from the machine one by one, the springs of the support move it upwardly so that the topmost article of the pile is at all times maintained in operative relation to the serrated rollers of the shaft 79. The spring of the operating member renders it unnecessary for the purchaser to return the operating member to its initial position, so that in effect all that is necessary to manipulate the machine is to pull the handle forward, the spring returning the handle to its original position, and completing the operation of dispensing the article.

In Figs. 13 and 14 I have shown a partly modified form of the machine, in which the casing 160, the sectional article-support 161, the article-dispensing means 162 and 163 as well as others of the structural details, are similar to the corresponding elements previously described. The mechanism for resiliently raising the article-support is of different construction, however, and includes a shaft 164 mounted within the casing at the lower, rear portion thereof and operatively connected with the article-support. The shaft has a laterally extending arm 165 which is secured at its free end to a spring 166. The opposite end of the latter is fastened by means of an adjustable connection 167, to a laterally disposed arm 168 carried by a lever 169. The lever is mounted to swing at its rear extremity and corresponds to the lever 77. When the lever is in a normal position, the spring 166 is under tension and resiliently elevates the support to bring the topmost article thereon in engagement with the serrated rolls of the dispensing mechanism. By means of the connection 167 the tension of the spring 166 can be varied as may be necessary or desirable. This form of the machine includes feed regulators 170, which in general construction and operation are similar to those already described. The present feed regulators however, have rearwardly disposed arms 171 provided at the ends with weights 172 so that the regulators are counterbalanced. Furthermore, they are provided with pivotal mountings 173, by means of which they are supported directly at the inner casing sides. Adjacent to each feed regulator the wall of the casing carries a spring keeper 174 having an offset end 175 of V-form adapted to engage at the end of a retaining finger 176, rigidly secured upon

the regulator. The keeper serves to hold the regulator in an inoperative position, as is shown in Fig. 15. When it is desired to render the regulators operative, it is merely necessary to swing them upward so that the fingers 176 are pressed beyond the ends of the keepers. These then serve to hold the regulators in the raised positions, in which they are well above the article-support and 10 out of engagement with the newspapers thereon.

Having thus described my invention, I claim as new and desire to secure by Letters Patent:

- 15 1. In a machine of the class described, a casing having an outlet, means for dispensing articles from the machine, through said outlet, operating mechanism for said means, a closure for said outlet, normally operative to obstruct the same, and means controlled by the article-dispensing means and independent of said operating mechanism, for displacing said closure from its operative position.
- 20 2. In a machine of the class described, a casing having an outlet, an article-support therein, means for dispensing the articles from said support, through said outlet, one at a time, said means including a roll for moving the article through the outlet, a normally operative closure for obstructing said outlet, and means operable by said roll, for displacing said closure.
- 25 3. In a machine of the class described, a casing having an outlet, an article-support within said casing, means for advancing articles from said support to said outlet and through the same, one at a time, said means including two rolls between which the article dispensed passes, one of said rolls being bodily movable, a normally operative closure for said outlet, and means operatively connecting said roll and said closure, whereby said closure is inoperatively disposed by the engagement of the article dispensed with said bodily movable roll.
- 30 4. In a machine of the class described, a casing having an outlet, means for dispensing articles from said casing, through said outlet, said means including a rotatable and bodily movable roll, a normally operative closure for said outlet, and an operative connection between said roll and said closure, whereby the bodily movement of said roll when the same engages the article dispensed, is multiplied and translated to said closure to displace the same from its operative position.
- 35 5. In a machine of the class described, a casing having an outlet, means for dispensing articles from said casing, through said outlet, said means including a rotatable and bodily movable roll, a normally operative closure for said outlet, a lever having a fixed fulcrum and operatively connected with said roll, and an operative connection between said lever and said closure.
- 40 6. In a machine of the class described, a casing having an outlet, means for dispensing articles from said casing, through said outlet, said means including a pair of rolls, one of which is bodily movable, a member operatively associated with said bodily movable roll and having a fixed fulcrum about which said member can pivot as said roll moves bodily, and a lever adapted to be engaged by said member, and operatively connected with said closure to displace the same when said lever is raised by the bodily movement of said roll, said member and said lever being proportioned to multiply the movement of said roll when the movement is translated to said closure.
- 45 7. In a machine of the class described, a casing, article-dispensing means therein including a shaft having rolls thereon, a fixed bearing for said shaft and a movable bearing for said shaft, whereby said shaft can be removed, said movable bearing comprising hinged members adapted to be arranged in different positions, in one of which said bearing is axially aligned with said shaft, said casing having a closure engaging said movable bearing when said closure is shut, to maintain said bearing in a normal, operative position with respect to said shaft.
- 50 8. In a machine of the class described, a casing, a closure for said casing, means for dispensing articles from said casing, a feed regulator for controlling the dispensing of the articles, and means whereby said feed regulator is inoperatively disposed when said closure is open.
- 55 9. In a machine of the class described, a casing having a closure, a support within said casing, for the articles to be dispensed, means for advancing the articles from said support to dispense the same, a feed regulator engaging the articles upon said support, and adapted to allow but one article at a time to be dispensed, and means whereby said feed regulator is inoperatively disposed when said closure is open.
- 60 10. In a machine of the class described, a casing having a closure, a support for the articles to be dispensed, means for advancing the articles from said support to dispense them, independently movable feed regulators adapted to adjust themselves automatically to the articles, at separated points, means for maintaining said regulators in normally operative positions, and means whereby said regulators are raised into inoperative positions when said closure is open.
- 65 11. In a machine of the class described, a casing having a closure, an article-support within said casing, a feed regulator adapted to engage the articles upon said support and to control the escape of the articles from

said casing, means for advancing the articles from said casing, a pivoted member operatively connected with said feed regulator, and a spring-pressed member connected with said pivoted member and adapted to be engaged by said closure, whereby said feed regulator is operatively positioned when said closure is shut.

12. In a machine of the class described, a casing having an outlet, an article-support within said casing, means for advancing articles from said support to said outlet, a feed regulator for controlling the movement of the articles from said support, and means whereby said feed regulator can be inoperatively positioned.

13. In a machine of the class described, a sectional article-support having relatively movable parts, means for raising said support, an arm rigid with one of the parts of said support, and a stop engaged by said arm.

14. In a machine of the class described, a casing having a movable article-support therein comprising relatively movable sections, means for dispensing articles from said support, means tending to raise said support, and an arm rigid with one of the sections of said support, said casing having a fixed stop engaged by said arm.

15. In a machine of the class described, a casing, an article-support therein comprising a normally horizontal part, and a second part hinged thereto and tending gravitationally to maintain an angular position relatively to said normally horizontal part, means tending to raise said support, an arm rigid with said second part of said support, and a fixed stop adapted to be engaged by said arm.

16. In a machine of the class described, a sectional article-support comprising a normally horizontal part and a second part hinged thereto, means tending to raise said support, means for guiding said support, a fixed stop disposed above said normally horizontal part of said support, and an arm rigid with said second part and in contact with said stop, whereby as said horizontal part of said support rises, said second part of said support moves into a position in the plane of said horizontal part.

17. In a machine of the class described, a movable article-support, means for guiding the movement of said article-support, a pivoted arm, a link connecting said arm and said article-support, and an adjustable spring tending to move said arm.

18. In a machine of the class described, a movable article-support, a rock shaft, a spring on said shaft, having one end fixed and the other end secured to said shaft, and an arm rigidly secured to said shaft and operatively associated with said support.

19. In a machine of the class described, a

casing having tracks, a movable article-support, carriages associated therewith and arranged to travel along the said tracks, a rock shaft, a spring on said shaft having one end fixed and the other end secured to said shaft, and an arm rigidly secured to said shaft and operatively associated with said support.

20. In a machine of the class described, a casing, a movable article-support guided in said casing, a rock shaft, a spring having one end fixed with respect to said casing and having the other end adjustably secured to said shaft, means for adjusting the tension of said spring, an arm rigid with said shaft and an operative connection between said arm and said support.

21. In a machine of the class described, a casing having an outlet, means for dispensing articles from said casing to said outlet, a normally operative closure obstructing said outlet, and means operated directly by the article itself, whereby said closure remains permanently closed when all the articles have been dispensed from the casing.

22. In a machine of the class described, a movable article-support, a member operatively connected therewith, a spring controlling said member whereby the same tends to raise said article-support, and a lever operatively connected with said member and adapted to be arranged in different positions, in one of which said support is held in a depressed position.

23. In a machine of the class described, a sectional article-support comprising relatively movable members, an arm rigid with one of said members, a fixed support adapted to be engaged by said arm, a pivoted arm operatively connected with said article-support, and a spring tending to raise said pivoted arm to raise said article-support.

24. In a machine of the class described, a sectional article-support comprising relatively movable members, an arm rigid with one of said members, a fixed stop adapted to be engaged by said arm, a pivoted arm operatively connected with said article-support, a spring tending to raise said pivoted arm to raise said article-support, a lever operatively connected with said last-mentioned arm, and means for holding said lever in position such that said support is held in a predetermined position against the tension of said spring.

25. In a machine of the class described, an operating member, article-dispensing means, and a flexible member for actuating said dispensing means, said flexible member having one end fixedly secured to said operating member and the other end adjustably secured to said operating member.

26. In a machine of the class described, an operating member, article-dispensing means controlled thereby, a stop normally

- operative to prevent movement of said operating member, and means whereby an initial movement of said member serves to displace said stop.
- 5 27. In a machine of the class described, an operating member, article-dispensing means controlled thereby, a normally operative stop preventing the movement of said member; a second, normally inoperative member adapted to be engaged, when operative, by said operating member, whereby an initial movement of said operating member serves to displace said stop, and means for rendering said second, normally inoperative member operative.
- 10 28. In a machine of the class described, an operating member, article-dispensing

means controlled thereby, a normally operative stop preventing the movement of said member, and a normally inoperative tongue adapted, when operative, to be engaged by said operating member, and, through an initial movement of said operating member to displace said stop, said tongue being adapted to be controlled by coin-control mechanism.

In testimony whereof I have signed my name to this specification in the presence of two subscribing witnesses.
